Primary Examiner — John M Otte

(57) **CLAIM**

The ornamental design for a computer display screen with graphical user interface, as shown and described.

DESCRIPTION

FIG. 1 is a front view of a computer display screen with graphical user interface showing our new design; FIG. 2 is a front view of a second embodiment thereof; and, FIG. 3 is a front view of a third embodiment thereof. The unevenly spaced broken line shows a computer display screen and forms no part of the claimed design. The other broken lines show portions of the graphical user interface which form no part of the claimed design.

1 Claim, 3 Drawing Sheets
